UNITED STATES PATENT OFFICE.

PATRICK P. LA MONTAGNE, OF BOURBONNAIS, ILLINOIS, ASSIGNOR, BY MESNE ASSIGNMENTS, TO POPE MACHINE COMPANY, OF KANKAKEE, ILLINOIS, A CORPORATION OF ILLINOIS.

KNITTING MACHINE.

Application filed December 7, 1917. Serial No. 205,979.

To all whom it may concern:

Be it known that I, PATRICK P. LA MONTAGNE, a citizen of the United States, residing at Bourbonnais, county of Kankakee, State of Illinois, have invented an Improvement in Knitting Machines, of which the following description, in connection with the accompanying drawing, is a specification, like characters on the drawing 10 representing like parts.

The invention has for its object the providing, in connection with a knitting machine of the type employing the so-called separate latch needles, that is, needles in 15 which the hook member and the co-operating latch member are physically separate and independent parts having relative bodily movement, of means for throwing these separate latch needles out of and into 20 knitting operation, or means for throwing such a needle out of action while retaining thereon a stitch ready for casting off over yarn next fed to the needle and for restoring the needle into action with the latch and hook 25 members in relation to receive the said next yarn fed before the said retained stitch is cast off. The primary practical importance of this feature of the invention is that it enables a knitting machine of this type utilizing 30 the separate latch needles to be employed in such knitting operations as those required in making hosiery where reciprocating knitting has to be performed and the needles thrown out of and into knitting 35 operation.

The invention also has for its object to provide such means acting selectively with respect to the needles by sets and selectively with respect to a given set of needles. In 40 this respect the invention provides knitting instrumentalities including the separate latch needle members in which these instrumentalities are of different types or sets, together with means for selectively throwing or positioning one set out of and into knitting operation independently of the other set, and also means for selectively

throwing selected instrumentalities of similar form, or of one set, out of and into knitting operation without dropping stitches. 50

The invention also provides a novel type of knitting instrumentality comprising a hook member, a latch member and a jack member, each of these members being relatively and bodily movable with respect to 55 the other and the jack member being operative on one of said first two members to move it with respect to the other.

The invention in certain aspects also relates to any type of knitting machine 60 wherein it is necessary to throw some of the needles out of action during the knitting operation, and hence in certain features the invention is not restricted to the separate latch needle. 65

More specifically considered the invention resides in providing in a knitting machine a needle of the separate latch type and a separate instrumentality herein termed for convenience a separate jack so arranged and 70 co-operating that the movement of the needle to upward, projected, or yarn-receiving, position is effected by the action of the cam upon the butt of the needle and the movement of the needle to downward, retracted, or casting off, position is effected by the action of the cam upon the separate 75 jack and therethrough to the needle and further so arranged and co-operating that the needle is thrown out of action by moving or elevating the separate jack to a position where it will not be acted upon by the depressing or retracting cam, thus preventing the needle from receiving a movement to downward, retracted, or casting off, 80 position. 85

The invention involves the combination of the separate jack with any type of needle as a simple and efficient arrangement by which any needle may be thrown out of and 90 into knitting operation, and the invention also involves the combination of the separate latch needle with the separate jack as a preferred and efficient arrangement for

embodying the broad principle by which the desired control of the separate latch needles in being thrown out of and into action is secured.

5 The invention thus provides means whereby needles, especially those of the separate latch type may be readily and easily thrown out of action and returned to knitting position, when required, with the minimum 10 amount of movement, with the minimum amount of friction and without danger of binding or breakage.

Furthermore, the invention in the feature of the separate jack provides an instrumentality which may be readily and cheaply and accurately manufactured because the separate jacks in their preferred form may be punched or stamped from sheet metal. Such a separate jack preferably 20 includes an integral butt upon which the depressing or retracting cam acts. So also the needle itself, and if of the separate latch type the hook member, is preferably also formed by a stamping or punching operation to present an integral butt upon which the elevating or projecting cam acts. Thus the cams of the knitting machine act upon butts which are formed with great accuracy and hence the movements of 30 the needle may be effected with great accuracy in both directions and without any substantial danger of breakage of the parts. The greatest strain in the operation of the machine naturally takes place in the depressing or retracting operation and as this operation is performed by the action of the retracting or depressing cam upon the butt of the jack the main wear and strain comes upon the jack itself. This instrumentality 40 being a separate part if it becomes worn or broken may be readily and easily replaced without requiring the removal or replacement of the needle.

Furthermore, as in this invention the 45 needle is thrown out of action by the movement of the jack to a position where it will not be acted upon by the depressing or retracting cam the needle is given no unusual or prolonged movement but remains in its 50 normal elevated position thus materially reducing the wear, friction and wedging or binding strains to which it would otherwise be subjected.

A further feature of the invention resides 55 in the fact that the separate jack is located on the outside of the needle and while therefore requiring a slightly increased diameter of cylinder or thickness of needle bed does not alter the effective diameter of the cylinder or the number or gage of the needles.

The invention also provides a simple and efficient means for enabling that particular type of separate latch needle, in which the reciprocating movements of the latch are 60 secured by spaced shoulders on the hook

member contacting in the respective reciprocations of the hook member with the latch, to be thrown out of action. Such type of separate latch needle cannot be thrown out of action as, for example, to enable the knitting of the heel and toe sections of a stocking and as, for example, to enable the narrowing and widening operations in the knitting of the heel and toe sections of the stocking without some special provision being employed.

These and other features of the invention will appear more fully from the accompanying description and drawings and will be particularly pointed out in the claims.

While the invention in some of its aspects is not to be restricted to the particular type of knitting machine nor to the particular type of needle employed, it is herein shown for purposes of illustration and to disclose its fullest application as embodied in a well-known circular type of knitting machine in which separate latch needles are employed.

Since the invention in this preferred embodiment does not alter the general construction and operation of the knitting machine it is unnecessary either to illustrate or describe in detail such general construction and operation because that is well known and familiar to those skilled in the knitting machine art.

In the drawings,

Figure 1 is a view chiefly in central vertical cross-section taken on the line A—A of Fig. 2 through the cylinder of an ordinary type of circular knitting machine equipped for reciprocating work and embodying a preferred form of the present invention;

Fig. 2 is a top plan view partially in horizontal section taken on the line B—B of Fig. 1 and partially broken away, and eliminating features unnecessary to a disclosure of the invention, of the construction shown in Fig. 1;

Fig. 3 is a detail chiefly in vertical cross-section taken on the line C—C of Fig. 2 of a portion of the cylinder of the machine and adjacent parts showing one of the picking instrumentalities for elevating the separate jacks to throw the needles out of action;

Fig. 4 is a diagrammatic view showing the general relation of the needle, separate jack, picker and cams when the jack is raised in position to throw the needle out of action;

Fig. 5 is a view similar to Fig. 4 showing the needle, separate jack, dropper and cams when the jack is depressed to bring the parts into knitting position;

Fig. 6 is a view similar to Fig. 4 showing a separate latch needle of that type wherein the latch member is given its reciprocating movements by spaced shoulders on the hook member shank;

Fig. 7 is a view similar to Fig. 5 showing a separate latch needle of the type shown in Fig. 6.

For the reasons already explained it is unnecessary either to illustrate or describe in detail the general features and construction of a knitting machine or of the knitting machine of the particular type herein illustrated. It will be sufficient to note with respect to this particular type of knitting machine herein illustrated for the purpose of disclosing the invention that it embodies a suitable circular bed plate 1 in which is centrally mounted a cylinder carrier 2 supported by a rod 3. On the cylinder carrier 2 is mounted the usual needle cylinder 4. Surrounding the needle cylinder and concentric therewith and supported by the bed plate is the usual skeleton cylinder 5 the spaces between the bars of which radially align with the needle grooves in the exterior wall of the cylinder.

The needle operating cams comprise the usual two sections 6 and 7, the lower section 6 being provided with the inclined cam surfaces 8 and the upper section 7 with the corresponding inclined surfaces 9, these surfaces co-operating in the usual manner, and as will hereafter be explained in connection with this invention, to effect the projecting and retracting movement of the needles in the knitting operation. The cam sections 6 and 7 are spaced much further apart than ordinarily because of the form of separate jack feature herein illustrated. The cam section 7 is supported from the cam carrier 12 and the cam section 6 is formed in or supported by the cam ring 10 surrounding and concentric with the skeleton cylinder 5 and provided at the bottom with a radially extending flange 11. The cam ring 10 telescopes within and is vertically movable with respect to and rotates on the cam carrier 12 which is mounted concentrically of the cam ring 10 upon the bed plate 1. The provision for vertical telescoping movement of the cam ring with respect to the cam carrier and the rotary movement of these parts together is effected by means of a stud 13 secured to the flange of the cam ring 10 and projecting through a hole in the flange of the cam carrier 12. The cam ring 10 rests upon a ring support 14 concentric with the skeleton cylinder and rigidly secured to the cylinder carrier by means of vertical studs 15 extending upwardly from lugs 16 projecting from the bottom of the cylinder carrier.

Such a construction as that described enables the cylinder and the cam ring and with it the lower operating cam 6 to be raised and lowered vertically to adjust the length of stitch drawn off by the needles.

The cam carrier and with it the cam ring and cams are given the required rotary or

oscillating movement from a gear ring 17 temporarily mounted in the bed plate 1 concentric of the cam carrier and provided at its bottom with the gear teeth 18 meshing with a bevel gear 19 operated in the usual manner 70 from a shaft 20.

The needles draw the yarn down over a suitable work-engaging portion 21 of the cylinder which is herein shown as the upper surface of the sinkers 22 of a familiar type 75 mounted to slide radially in grooves in a sinker cylinder 23 secured at the upper end of the cylinder 4.

While in certain aspects of the invention the needles may be of any suitable type the 80 invention is particularly concerned with the separate latch type of needle two forms of which are herein illustrated in Figs. 1 to 5 and Figs. 6 and 7, respectively. In the construction shown in the former figures the 85 separate latch needle comprises a hook member 24 and a separate latch member 25. This needle is of the general type illustrated in the patent to Pope and Randall No. 1,096,945 granted May 19, 1914. The hook member 24 90 is formed at its upper end with the usual hook 26 and at the lower end of its shank with a butt 27 preferably punched or stamped out integrally with the shank to form an accurately and sharply defined portion. Adjacent the hook the hook member is slotted longitudinally and transversely. The hook member slides in the usual groove in the exterior wall of the cylinder. The latch member which is much thinner than 100 the hook member comprises a shank 28 fitting in and sliding in a narrower slot formed in the cylinder in the rear of or beneath the slot for the hook member and a head 29 provided with a point 30 projecting and 105 movable through the longitudinal slot in the hook member. Suitable shoulders 31 and 32 on the head of the latch member co-operate with corresponding shoulders formed by the end walls of the slot in the 110 hook member to cause the latch member to be reciprocated from the hook member. The tail of the latch member 28 is bent to cause it frictionally to engage the side walls of its slot. Accordingly upon the principle described in the aforesaid Patent No. 1,096,945 when the hook member is projected or elevated it leaves the latch member behind until the shoulder 32 comes into contact with the corresponding shoulder in the hook 115 member. The yarn is then fed to the hook member and on the reverse reciprocation of the needle the hook member retracts, the latch member being held by friction in its slot until the hook rides into the position 120 to be covered by the point 30 of the latch member whereupon the shoulder 31 contacts with the corresponding shoulder on the hook member and the two members of the needle move together casting off the yarn. The 125 130

term latch member as used herein, and unless otherwise limited, is to be understood as comprehending any member constituting a permanent part of each needle and co-operating with the hook member of the needle to secure the casting off over the hook of the stitch.

In the present invention a third member is provided herein termed a separate jack.

10 The preferred embodiment of this device is illustrated as a thin flat bar 33 provided between its ends with a radially projecting butt 34 and above the butt with an offset 35. This separate jack is preferably formed by 15 a punching or stamping operation so that the butt 34 presents sharply defined edges accurately positioned with respect to the body of the jack. When in position the separate jack is located in the same groove 20 with a corresponding hook member of the needle and with its butt 34 projecting radially in line with and to the same extent as the corresponding butt 27 of its needle. The butt 34 is so positioned with respect to the 25 length of the jack 33 that the space between the butt 34 of the jack and the butt 27 of the needle is sufficient to allow the usual picker mechanism and elevating cam for throwing the needles out of action to enter 30 beneath the butt 34 without engaging the butt 27. It is by reason of the separate jack and to allow the operation of the picker and elevating cam on the butt of the separate jack that the cam section 7 is spaced much 35 further than usual from the cam section 6.

The offset 35 upon the separate jack member corresponds to the usual offset on the needle and is transferred to the jack member therefrom. This offset co-operates with 40 the usual spring ring 36 surrounding the needles, and now transferred to surround the separate jacks, so that as the jacks are moved up the offset 35 rides over the spring 36 and the jacks are thereby held in elevated 45 position.

The operation of the machine in ordinary circular knitting will now be apparent. As the cam ring rotates the surface 9 on the depressing cam section 7 rides over the top 50 surface of the butt 34 on the jack and depresses the jack carrying with it the hook member of the needle because the lower end of the jack rests against the butt 27 of the hook member. Thus the cam surface 9 moves the jack and hook member together 55 and, as it picks it up, the latch member also down to casting off position. As the cam continues its rotation the cam surface 8 on the lower cam section contacting with the 60 lower surface of the butt 27 of the hook member projects the needle and with it the separate jack 33 projecting the hook member away from the latch member until the hook is uncovered and then picking up the latch 65 member and carrying the three parts, that

is, the separate jack, the hook member and the latch member, to the projected or yarn-receiving position. In this operation the jack and hook member move together and the action is the same as if they were integral.

When, however, the machine changes from circular work to reciprocating work and back again, as for example in the knitting of the heel and toe sections of a stocking, 75 it is necessary, first, to throw one section of needles entirely out of action as for example those needles which are concerned with the knitting of the instep and, then, gradually to narrow the work by throwing 80 out of action one or more needles of the remaining section at each end of each reciprocation whereby the work is narrowed to the required point. Thereafter the work is gradually widened by the bringing back into 85 action one or more needles of the latter section at each end of each reciprocation, and finally the needles of the section first thrown out of action are restored to knitting position. It will thus be seen that there are 90 essentially provided for this type of work two sets or types of needles, usually distinguished by the shape of the butt, and that one of these sets of needles may automatically be selected and thrown out of and into 95 knitting operation independently of the other set. It will also be seen that selected needles of similar type, or of one set, may be thrown out of and into knitting operation as required in order to perform this 100 important part of the knitting operation.

Any suitable or well known type of mechanism may be employed in connection with the separate jack needle in which this invention is embodied making only such slight 105 changes of adjustment and position as are necessary to adapt it to use in connection with this separate jack. For this purpose a well known type of mechanism, familiar to those skilled in the art and in its main 110 features shown in the patent to Mayo, No. 726,178 granted April 21, 1903, is illustrated and the details of its construction and operation it is unnecessary here to describe at length because they are well known to those 115 skilled in the knitting art.

The phrase "thrown out of action" herein employed is to be understood as a broad and inclusive expression for the bringing about of that condition whereby the needle 120 is rendered inactive or the normal knitting operation ceases, which occurs in the particular embodiment of the invention illustrated when the normal reciprocating stroke of the needle ceases or is suspended, or the 125 elements of the knitting instrumentality assume a particular position in the multiphase movement of the members. A needle thus "thrown out of action" does not cast off yarn or form a stitch during the relative lateral 130

movement of the needles and knitting cams. Familiar examples of needles thus "thrown out of action" are those rendered inactive when reciprocating knitting begins, and 5 those rendered inactive in the narrowing operation in the knitting of the toe and heel pockets of hosiery.

Ordinarily in throwing a needle out of action the needle butt of the needle is acted 10 upon by a cam or a picker mechanism which elevates or projects the butt out of the path of the depressing or retracting cam surfaces 9 thus projecting or elevating the needle to a position much beyond that required in any 15 of the knitting operations. And when the needle is returned to knitting position the butt of the needle is acted upon by a cam or dropper mechanism which depresses or retracts the needle into the path of the depressing or retracting cam surfaces 9. In 20 the present invention the needle is left in its normally elevated or projected position and the separate jack is acted upon by suitable mechanism such as the ordinary cam and 25 picker mechanism whereby the separate jack is elevated or projected to a position in which its butt is out of the path of the retracting or depressing cam surfaces 9, and the separate jack is subsequently acted upon 30 by suitable mechanism such as a cam or dropper mechanism acting upon its butt to depress or restore it into the path of the cam surfaces 9. Hence as the cams revolve the separate jack remains elevated or projected 35 and consequently the needle remains in its normally elevated or projected position and out of action, and when the needle is to be brought into action suitable mechanism such as the cam or dropper mechanism acts upon 40 the butt of the separate jack to restore or depress it into the path of the depressing cam surface 9. Thus there is no tendency to wear, bind or wedge the needle in throwing 45 it out of action and the cross sectional area of the needle is not enlarged by projecting it with its separate latch as in the case of a separate latch needle above its normal elevated or projected position. Furthermore, the action of the cam, picker 50 mechanism and dropper mechanism takes place entirely upon the butt of the separate jack so that the strains and the wear due to the throwing of the needles into and out of action is taken up by the jack and if the jack 55 becomes worn or broken it may be readily and easily replaced without disturbing the needle.

The set of needles which are thrown out of action when reciprocating knitting is to 60 take place and which remain out of action holding the yarn are usually selected by being provided with butts of greater radial length than the butt of those needles which are to continue in action and perform re-

ciprocating knitting and the same principle 65 is here employed. Such needles and their corresponding jacks therefore have their butts 27 and 34 respectively of greater length than the other needles. This set of needles may be thrown out of action by a 70 suitable wedge-shaped switch cam 37 mounted upon a shaft 38 rotatably and longitudinally movable in a bearing 39 radially supported from the gear ring 17. This cam 37 during the ordinary circular knitting operation stands in elevated position and travels in a path above the butts 34, the elevated cam thus clearing all the butts. When the set of needles having the longer butts are to be thrown out of action the shaft 38 is rotated and at the same time moved longitudinally outwardly to bring the point of the cam 37 into its depressed position below the path of the butts 34 of the separate jacks which have the longer set of butts. This 80 movement of the cam 37 may be effected manually or automatically in the latter case by some means such as the automatic positioning of the cam 40 in the path of the crank arm 41 extending from the shaft 38. 85 In this depressed position as the gearing is rotated the upper surface of the cam 37 rides beneath the butts of the jacks having the longer butts and raises or projects the jacks to a position where they are caught 90 by the cam surface 41 on the cam section 7 and are further elevated thereby and ride along the surface 42. The needles themselves corresponding to these jacks are projected no further than they are in the normal knitting operation by the cam surfaces 8 and hence remain in their normal projected position. The jacks being out of 95 reach of the depressing or retracting cam surfaces 9 remain out of action and consequently the corresponding needles themselves remain out of action. 100

When this section of needles is to be restored to knitting position the cam 37 is swung upwardly and at the same time 110 moved inwardly, the latter action being effected as by a stud 43 on the shaft 38 riding in an inclined groove 44 in the bearing 39 to bring the lower surface of the cam 37 above the butts 34 of all the needles, both 115 those having the longer and those having the shorter butts, so that as the cam ring is rotated the needles are all retracted or restored to a position where they are within the path of the depressing or retracting cam surfaces 120 9. This operation may be performed either manually or by the usual type of automatic mechanism of the machine.

In the formation of reciprocating work such as the knitting of the heel and toe sections of a stocking after one section of needles such as those having the longer butt are thrown out of action it is necessary gradu-

ally to reduce the number of the needles remaining in action and then gradually to restore these needles to knitting action. This is usually accomplished by throwing out of 5 action successively one or more needles at each end of each reciprocation and then bringing back into action one or more needles at each end of each reciprocation. This is accomplished in the ordinary knitting ma- 10 chine by the use of suitable mechanism such as a picker mechanism and a dropper mechanism, the former acting to elevate or project the needles successively and the latter acting subsequently to depress or restore the 15 needles successively. Any suitable mechanism may be used for this purpose and a well known type familiar to those skilled in the art is illustrated in its general features. In this invention the picker and dropper mech- 20 anism instead of acting upon the butts of the needles is so adjusted and arranged as to act upon the butts of the separate jack members and respectively picks and depresses the jack butts out of and into the path of the retract- 25 ing or depressing cam surfaces 9.

In the construction illustrated the picker mechanism and the dropper mechanism are shown as separate instrumentalities. When the reciprocating knitting is taking place 30 the gear ring 17 is given an oscillating or reciprocating motion. Upon this gear ring at one side are mounted the pickers 45 and at an opposite point the dropper 46 and all are constructed and operated in a manner well 35 known to those skilled in the art except that the effective ends of the pickers and dropper are adjusted to co-operate with the butt of the jack rather than the butt of the needle and act to shift the jack butt out of and into 40 the path of the depressing or retracting cam surfaces 9.

The pickers 45 at their effective ends are notched at 47 sufficiently to receive the butts of one or more needles according to the number 45 to be thrown out of action at each end of each reciprocation. Each picker 45 is mounted to pivot vertically in a post 48 and each post is mounted to pivot horizontally on the gear ring 17. The shanks of the pickers ex- 50 tend through cam slots 49 in a guide plate 50 also secured to the gear ring. The lengths of the pickers are such that when in radial po- 55 sition the pickers will just clear the skeleton cylinder and the heads of the pickers will pass above or beneath the jack butts so that 60 during circular knitting the pickers are idle. The posts 48 are spaced apart a distance longer than the amount of lost motion be- 65 tween the gear ring and cam carrier so that 60 at each change of direction of movement the cam carrier operates to carry first one and then the other of the pickers into position in front of the cam section 7 trailing the other picker upon the outside of the said cam,

but neither picker can be trailed behind the 65 cam section without causing it to swing horizontally with the post 48 and clear the said cam. This swinging movement in co-operation with the cam surfaces on the guide plate 49 causes the swinging picker to be depressed 70 into its lowermost position. When the direction of reciprocation is again changed this depressed picker is by the lost motion be- 75 tween the gear ring and cam carrier brought in front of the cam surface 9 in its lower- 80 most position and its notch 47 will thereupon engage the butt or butts of the separate jacks to be elevated or projected. As the rotation of the gear ring continues the jack butts thus seized hold the picker against rotation 85 and the picker slides up the cam surface on the guide plate 50 and takes with it the en- gaged jack butts until these jack butts are in line with the cam surface 41. The jacks are then lifted by the cam surface 41 onto the 90 surface 42 and the jacks are held in this po- 95 sition by the offsets 35 riding over the spring 36. The picker then clears itself from the jack butts as the jacks are forced upward by the cam surface 41 and springs back into 95 its normal radial position. This operation continues reversely with the two pickers and thus at each end of each reciprocation one or more jacks are elevated or projected and thus the corresponding needles are brought 100 out of action and thus the knitting is gradu- ally narrowed.

The widening operation then takes place in a similar but reverse manner through the action of the dropper 46 which is a 100 symmetrically shaped device horizontally and vertically pivoted in a bearing 51 on the gear ring 17. This dropper 46 is notched at each side and at the bottom of its end to re- 105 ceive the butts of one or more of the jacks ac- cording to the number to be depressed at the end of each reciprocation. It stands out of the path of the jack butts and when called into operation preferably by automatic mech- 110 anism, such, for example, as the sliding cam plate 52 automatically actuated by the crank arm 53 in the mechanism of the ma- chine, at the required time it is guided to a position in line with the butts of the ele- 115 vated or projected jacks so that at the 115 end of each reciprocation the jack butts at the end of the row of needles out of action ride into one of the notches in the end of the dropper. As the reciprocating move- 120 ment continues the dropper is forced down- wardly in the cam slot of its guide plate, herein not shown for clearness of illustration, carrying with it and thus depressing the butts of the engaged jacks and as it is carried downwardly it swings radially and 125 clears itself after depressing the jacks. The dropper then springs back into elevated po- 125 sition and is operated upon the reverse re-

ciprocation in a similar manner. In the widening operation the dropper is generally arranged to depress a greater number of jacks than the pickers elevate, for example 5 the pickers may remain in operation each elevating say one jack at the end of each reciprocation and the dropper depressing two jacks at each end of each reciprocation so that as a net result one jack is brought 10 back into operative position at each end of each reciprocation and thus the widening of the knitting secured. But the particular construction and operation of the picker mechanism and the dropper mechanism is 15 not involved in this invention and this general explanation will be sufficient to those skilled in the art.

As already explained after the widening action has been completed the switch cam 20 37 is projected inwardly and elevated so as to extend over the butts of all the jacks, both those of the longer and shorter type, and thus the depressing or retracting movement of all the jacks and consequently 25 of all the needles is insured.

It is important that the hook member and the latch shall always retain when in yarn-receiving position a fixed relation to the work-engaging portion or top of the cylinder, in the form shown, the top of the sinkers. This requirement is particularly 30 true of the separate latch needle and of the latch member thereof. It is frequently desirable to vary the length of the loop by 35 varying the extent to which the needle is depressed or retracted, the yarn being drawn out by the cylinder needle over the dial needles when a dial is employed or over the top of the cylinder when a dial is not employed. The lengthening of the stitch is 40 accomplished by changing the relative position of the cylinder and the retracting or depressing cam 7 to increase the distance therebetween. For this purpose well known 45 means may be employed for raising the supporting rod 3 and therewith the cylinder with respect to this cam. In order that the latch member may occupy when in yarn-receiving position always the same relation 50 to the top of the cylinder this invention provides for floating the lower or projecting cam 6 along with the cylinder. As a preferred means of securing this result the construction already described may be employed. That is, the ring support 14 is 55 arranged to move vertically with the cylinder and as the cam 6 is supported or formed in this ring this cam also floats or moves vertically with the cylinder. The elevating or 60 projecting cam therefore brings the jack and thereby the hook member and latch member to the same relation with the top of the cylinder whatever vertical adjustment may be given to the cylinder. Conse-

quently the path between the cam 7 and the 65 cam 6 when the cylinder is in its highest position of adjustment must be not less than sufficient to permit the jack and needle butts to pass.

In the construction already described the 70 latch member 25 receives its movement from the hook member 24 through the co-operation of the shoulders 31 and 32 on the head of the latch member with the shoulders formed by the end walls of the longitudinal 75 and transverse slot in the hook member. Such co-operating shoulders may be variously located in this type of needle and in Figs. 6 and 7 another form is shown wherein the hook member 54 is provided with shoulders 55 and 56 punched or stamped in the shank of the hook member at some distance from the longitudinal and transverse slot through the hook member and the latch member is provided with a shouldered butt 80 57 located between and co-operating with the shoulders 54 and 55. This construction enables a more accurate relative movement of the two needle members to be secured principally because when the shoulders on 90 the hook member are formed by the end walls of the slot they are more or less inaccurately formed because the slot is usually cut out by a saw. In this construction illustrated the needle is shown in Fig. 6 in its 95 elevated or projected yarn-receiving position. The hook member has been moved to this position by the cam surface 8 and in this movement the shoulder 56 has contacted with the lower shoulder of the butt 57 of 100 the latch member and carried the latch up with it. When the needle is lowered or retracted the cam surface 9 acting upon the butt of the jack 33 brings the jack into contact with the butt 58 of the hook member 105 and the hook member is then retracted until the shoulder 55 of the hook member comes in contact with the other shoulder of the butt 57 of the latch member. During this movement the tip 59 of the latch member rides up 110 the inclined end wall 60 of the slot in the hook member and closes over the tip of the hook and the two members then travel together in this position, casting off the loop, to the retracted or lower position. 115

In the construction shown in Figs. 6 and 7 the elevating or projecting cam 6 floats with the cylinder in the manner already described and the picker 45 and dropper 46 as well as the switch cam 37 have the action already 120 described, so that this form of needle is thrown out of action by shifting the jack in the manner already described.

The invention therefore provides means by which the separate latch type of needle, 125 in which the latch member is operated through the co-operation of shoulders thereon with shoulders on the hook member, is

thrown out of and into action without causing the movement of the needle members beyond that required in the normal knitting operation and consequently without increasing the cross-sectional area of the needle engaged by the loop, a feature which is of great importance in the operation of the separate latch member.

While but one set of operating cams 6 10 and 7 have been illustrated and described it will of course be understood that as many such operating cams shall be employed as there are yarn feeds.

It will also be understood that such terms 15 as "top" "bottom" "elevated" and "depressed" when used in the specification and claims are terms of relation and not of limitation and are used merely for convenience.

Having fully described my invention, 20 what I claim as new and desire to secure by Letters Patent is:

1. A knitting machine comprising a needle provided with a laterally extending butt, a separate jack for said needle, slideable with, 25 and with respect to, said needle and provided with a laterally extending butt, and cams acting upon the top of the jack butt and the bottom of the needle butt to effect the reciprocation of the needle in yarn drawing and loop casting off.

2. A knitting machine comprising the elements defined in claim 1 together with means acting upon the jack butt to move it out of and restore it into the path of its cam and thereby to throw the needle out of, and into 35 action.

3. A knitting machine comprising a needle consisting of a hook member and a separate latch member, the hook member 40 provided with a laterally extending butt and the latch member reciprocated through the medium of the hook member, a separate jack for said needle, slideable with, and with respect to, said hook member and provided 45 with a laterally extending butt, and cams acting upon the top of the jack butt and the bottom of the hook member butt to effect the reciprocation of the needle members in yarn drawing and loop casting off.

50 4. A knitting machine comprising the elements defined in claim 3 together with means acting upon the jack butt to move it out of and restore it into the path of its cam and thereby to throw the needle out of, and into 55 action.

5. A knitting machine comprising a needle, a separate jack therefor, movable both therewith and with respect thereto, means for reciprocating the needle acting 60 jointly upon the needle and its jack and means for suspending the reciprocation of the needle by moving the jack with respect to its needle.

6. A knitting machine comprising a

needle, a separate jack therefor, movable 65 both therewith and with respect thereto, means for causing the joint retracting movement of the needle and jack acting upon or through the jack and for causing the projecting movement of the needle acting directly upon the needle and means for suspending the reciprocation of the needle to throw it out of operation by giving a projecting movement to the jack independently of the needle. 75

7. A knitting machine comprising a needle, a separate jack therefor, movable both therewith and with respect thereto, means for reciprocating the needle and jack in unison to effect the knitting operation 80 and means for suspending the reciprocation of the needle by effecting a relative longitudinal movement of the needle and its jack.

8. A knitting machine comprising a 85 needle, a separate jack therefor movable longitudinally with and with respect thereto, and means for suspending the reciprocation of the needle by moving the jack longitudinally with respect to the needle. 90

9. The combination in a knitting machine of a needle provided with a laterally extending butt and a jack having a shank extending longitudinally of and in front of the needle with a butt extending laterally parallel with and at a distance from the needle butt, the lower end of the shank of the jack normally contacting with the needle butt whereby pressure on the upper portion of the jack butt will give a retracting movement and pressure on the lower portion of the needle butt will give a projecting movement to the needle, and means acting upon the jack butt to effect an upward movement of the jack independently of the needle for 100 the purpose of suspending the operation of the needle. 105

10. A knitting machine comprising a grooved needle bed, needles longitudinally slideable in said grooves and provided with laterally extending butts, separate jacks for said needles each presenting a shank and a laterally extending butt and mounted to slide in said grooves with, and with respect to, their respective needles, and a cam member movable relatively transversely to said needle bed and provided with a groove straddling the jack and needle butts and acting to effect the joint reciprocation of the respective needles and jacks. 110 115

11. A knitting machine comprising the elements defined in claim 10 together with means acting selectively upon the jack butts to move the selected jack butts out of, and restore them into, the path of said cam and thereby to throw the selected needles out of, and into, action. 125

12. A knitting machine comprising the

elements defined in claim 10 together with means for reciprocating the cam member with respect to the needle bed and picker mechanism acting at each end of each reciprocation to contact with a selected number of jack butts and move them out of the path of said cam thereby throwing the corresponding needles out of action.

13. A knitting machine comprising the elements defined in claim 12 together with a dropper mechanism acting at the end of each reciprocation selectively upon the jack butts of needles out of action to restore the said jack butts into the path of the said cam and thereby to restore the corresponding needles into action.

14. A knitting machine comprising a needle consisting of a hook member provided with a laterally extending butt and a separate latch member each member being provided with a pair of oppositely disposed shoulders, the separation of the shoulders of the one pair being greater than that of the other pair to an extent sufficient to secure the required relative movements of the members, a separate jack for said needle slideable with, and with respect to, said needle and provided with a laterally extending butt, and cams acting upon the top of the jack butt and the bottom of the needle butt to effect the reciprocation of the needle in yarn drawing and loop casting off.

15. A knitting machine comprising the elements defined in claim 14 together with means acting upon the jack butt to move it out of and restore it into the path of its cam and thereby to throw the needle out of and into action.

16. A knitting machine comprising the elements defined in claim 14 together with means for suspending the reciprocation of the needle by moving the jack with respect to its needle.

17. A knitting machine comprising a needle, a separate jack therefor movable with the needle to effect the retracting movement thereof, a cam engaging the jack to effect the said retracting movement, and means for suspending and restoring said retracting movement acting by shifting the jack longitudinally with respect to the needle out of and into engagement with said cam.

18. A knitting machine comprising a needle bed, needles longitudinally reciprocable therein each provided with a laterally extending butt, a separate jack for each needle slideable with and with respect to said needle and provided with a laterally extending butt, a retracting cam acting upon the top of the jack butt, a projecting cam acting upon the bottom of the needle butt, means for simultaneously adjusting the needle bed and projecting cam with respect to the retracting cam whereby the length of stitch may be varied without

varying the relation between the top of the needle bed and the needle when in yarn-receiving position.

19. A knitting machine comprising a series of needles, a corresponding series of jacks each movable with and with respect to its needle, means for reciprocating the needles to effect the knitting operation acting jointly upon each needle and its jack, and automatically controlled means for selectively moving said jacks with respect to their needles in one direction thereby to suspend the reciprocation of the selected needles and for selectively moving said jacks with respect to their needles in the opposite direction thereby to restore the reciprocation of the selected needles.

20. A knitting machine comprising a series of needles, a corresponding series of separate jacks therefor movable both with and with respect to the needles, means for jointly reciprocating each needle and its jack to effect the knitting operation, means for automatically and selectively projecting the jacks with respect to their needles thereby to suspend the knitting operation of the selected needles, and means for automatically and selectively retracting the jacks with respect to their needles thereby to effect the restoration of the knitting operation of the selected needles.

21. A knitting machine comprising a series of needles and a corresponding series of jacks therefor slideable both with and with respect to the needles, means for jointly reciprocating each needle and its jack to effect the knitting operation, and a picker and dropper mechanism acting selectively on the jacks to effect suspension and restoration of the knitting operation of the selected needles.

22. A knitting machine comprising a needle bed, needles longitudinally reciprocable therein, separate jacks for said needles slideable with, and with respect to, their respective needles and provided with laterally extended butts, means for projecting the needles, a retracting cam acting upon the jack butts for retracting the jacks and therethrough the needles, and means for simultaneously adjusting the needle bed and projecting means with respect to the retracting cam whereby the length of stitch may be varied without varying the relation between the top of the needle bed and the needles when in yarn receiving position.

23. A knitting machine comprising a needle bed, needles reciprocable therein, separate jacks for said needles longitudinally slideable with, and with respect to, their respective needles, and means to slide a series of said jacks longitudinally with respect to their needles thereby to render the said needles inoperative in the knitting operation.

24. A knitting machine comprising a separate latch needle having relatively bodily movable hook and latch members, means for moving the needle to effect the knitting function, and means for throwing the needle out of action while retaining thereon a stitch ready for casting off over yarn next fed to the needle and for restoring the needle into action with the latch and hook members in relation to receive the said next yarn fed before the said retained stitch is cast off.

25. A knitting machine comprising a separate latch needle having relatively bodily movable hook and latch members, means for effecting a relative movement between the needle and the yarn to perform the knitting function, and means for throwing the needle out of action while retaining thereon a stitch ready for casting off over yarn next fed to the needle and for restoring the needle into action with the latch and hook members in relation to receive the said next yarn fed before the said retained stitch is cast off.

26. A knitting machine comprising separate latch needles having relatively bodily movable hook and latch members, each needle having a normal reciprocating stroke for the knitting operation, means for selectively discontinuing such normal stroke of certain of the needles to render said needles inactive for the knitting operation, while retaining thereon stitches ready for casting off over yarn next fed to the said needles and for effecting resumption of the said normal stroke of the said needles with the latch and hook members in relation to receive the said next yarn fed, before the said retained stitches are cast off.

27. A knitting instrumentality comprising three co-operatively associated, but physically independent, hook, latch, and jack members, movement of the latch member being controlled by the hook member, and movement of the hook member being controlled by the jack member, without disturbing the yarn receiving relation of the latch and hook members.

28. In a knitting machine the combination of a longitudinally reciprocable needle comprising a hook member and a separate latch member, slidably mounted on the hook member, and operated thereby, and means associated with the hook member for effecting at times its inaction and for restoring it into action.

29. A knitting instrumentality comprising a hook member, a latch member, and a jack member, each relatively and bodily movable with respect to the other, the jack member being operative on one of said first two members to move it with respect to the other.

30. A knitting instrumentality comprising a hook member, a latch member, and a jack

member, each relatively and bodily slidable longitudinally with respect to the other, the jack member being operative on one of said first two members to move it with respect to the other.

31. A knitting instrumentality comprising a longitudinally reciprocable needle having a hook member and a separate latch member mounted for sliding movement relatively to the hook member and also movable under the influence of the hook member, means associated with the hook member and having a plurality of adjustable positions such that, when in one of these positions, inaction of the hook member results, the said means being actuatable to effect action of the hook member during the knitting operation, and means for effecting a combined movement of the said means associated with the hook member and the hook member.

32. A knitting machine comprising a needle bed provided with a series of grooves, a reciprocable needle in each of the grooves comprising a hook and a latch member, the said hook member being positionable in its groove for action and inaction during knitting, the latch member having a bodily sliding movement relatively to the hook member, and means in the groove and movable with respect to the needle for changing the relation between the hook and latch members.

33. A knitting machine comprising a needle bed provided with a series of grooves, a reciprocable needle in each of the grooves comprising a hook member and a latch member, the said hook member being positionable in its groove for action and inaction during knitting, the latch member having a bodily sliding movement relatively to the hook member, co-active means carried by the hook and latch members for effecting movement of the latch member from the hook member, and means movable with respect to the needle and associated with and operating on the hook member in its groove for effecting movement thereof and there-through movement of the latch member.

34. A knitting machine comprising a three element knitting instrumentality, the said elements being physically separate and including a hook member, positionable for action and inaction during knitting, a latch member relatively slidable with respect to the hook member for a multiphase movement in respect thereto, and a jack member associated with the hook member for rendering the hook member inactive without projecting it abnormally, the said jack member being movable in one direction independently of the hook member.

35. A knitting machine comprising a separate latch needle having relatively bodily movable hook and latch members, means for moving one of said members and there-

- through the other member to effect the knitting function, and means for throwing the needle out of action while retaining thereon a stitch ready for casting off over 5 yarn next fed to the needle and for restoring the needle into action with the latch and hook members in relation to receive the said next yarn fed before the said retained stitch is cast off.
- 10 36. A knitting machine comprising a separate latch needle having relatively bodily movable hook and latch members, means for moving the needle to effect the knitting function, and means for throwing 15 the needle out of action while retaining the hook member within the limits of its normal movement and retaining a stitch ready for casting off over yarn next fed to the needle and for restoring the needle 20 into action with the latch and hook members in relation to receive the said next yarn fed before the said retained stitch is cast off.
37. A knitting machine comprising a 25 separate latch needle having relatively bodily movable hook and latch members, means for moving the needle to effect the knitting function, and means for throwing the needle out of action while retaining the 30 latch member within the limits of its normal movement and retaining a stitch ready for casting off over yarn next fed to the needle and for restoring the needle into action with the latch and hook members in 35 relation to receive the said next yarn fed before the said retained stitch is cast off.
38. A knitting machine comprising a 40 separate latch needle having relatively bodily movable hook and latch members, means for moving the needle to effect the knitting function, and means for throwing the needle out of action by suspending the 45 normal movement of the hook member while in substantial yarn receiving position with a stitch thereon ready for casting off over yarn next fed to the needle and for restoring the needle into action with the latch and hook members in 50 relation to receive the said next yarn fed before the said retained stitch is cast off.
39. A knitting machine comprising a 55 separate latch needle having relatively bodily movable hook and latch members, means for moving the needle to effect the knitting function, and means for throwing the needle out of action while retaining the hook member substantially at or rearward of the forward limit of its normal projec- 60 tion and retaining a stitch ready for casting off over yarn next fed to the needle and for restoring the needle into action with the latch and hook members in relation to receive the said next yarn fed before the said retained stitch is cast off.
40. A knitting machine comprising a 65 separate latch needle having relatively bodily movable hook and latch members, means for moving the needle to effect the knitting function, and means for throwing the needle out of action by suspending the 70 normal movement of the hook member with a stitch thereon ready for casting off over yarn next fed to the needle and for restoring the needle into action by resuming the 75 normal movement of the hook member with the latch and hook members in relation to receive the said next yarn fed before the said retained stitch is cast off.
41. A knitting machine comprising a 80 separate latch needle having relatively bodily movable hook and latch members, means for moving the needle to effect the knitting function, and means for throwing the needle out of action while retaining the 85 hook member within the limits of its normal movement and retaining on the needle a stitch ready for casting off over yarn next fed to the needle and for restoring the needle into action with the latch and hook 90 members in relation to receive the said next yarn fed before the said retained stitch is cast off.
42. A knitting machine comprising a 95 separate latch needle having relatively bodily movable hook and latch members, means for moving the needle to effect the knitting function, and means for throwing the needle out of action while retaining the hook member substantially at or rearward 100 of the forward limit of its normal projection and retaining a stitch on the needle ready for casting off over yarn next fed to the needle and for restoring the needle into action with the latch and hook members in 105 relation to receive the said next yarn fed before the said retained stitch is cast off.
43. A knitting machine comprising a 110 separate latch needle having relatively bodily movable hook and latch members, means for moving the needle to effect the knitting function and means for throwing the needle out of action while retaining a 115 stitch ready for casting off over yarn next fed to the needle and for restoring the needle into action with the latch and hook members in relation to receive the said next yarn fed before the said retained stitch is cast off.
44. A knitting machine comprising a 120 separate latch needle having relatively bodily movable hook and latch members, means for moving one of said members and therethrough the other member to effect the knitting function, and means for throwing the needle out of action while retaining a 125 stitch ready for casting off over yarn next fed to the needle and for restoring the needle into action with the latch and hook members in relation to receive the said next yarn 130

fed before the said retained stitch is cast off.

45. A knitting machine comprising a separate latch needle having relatively bodily movable hook and latch members, means for moving the needle to effect the knitting function, and means for throwing the needle out of and restoring it into action with the said members maintained in yarn-

receiving relation and with a stitch retained ready for casting off over yarn next fed to the 10 needle whereby a continuous plain web will be knit by the needle when restored into action.

In testimony whereof, I have signed my name to this specification.

PATRICK P. LA MONTAGNE.
